UNITED STATES PATENT OFFICE.

GRANVILLE E. PALMER, OF BROOKLINE, MASSACHUSETTS, ASSIGNOR, BY MESNE ASSIGNMENTS, TO THE PALMER ELECTRIC & MANUFACTURING CO., OF WALTHAM, MASSACHUSETTS, A CORPORATION OF MASSACHUSETTS.

SAFETY SWITCH.

Application filed May 11, 1925. •Serial No. 29,286.

This invention relates to electrical switches, particularly to that type of switch which is combined with a circuit closing fuse, and which is commonly known as a safety switch. 5 Switches of this kind are most frequently employed as service switches for controlling the admission of current from a power line to the premises of a purchaser, and are installed between the power line and the meter 10 which measures the current delivered.

These switches with their fuses are ordinarily installed in closed and locked containers to prevent surreptitious diversion of current at the power-line side of the meter. 15 To permit renewal of the fuse without opening the box and without danger to the operator, it is common to provide the wall of the container at a point opposite to the fuse with an aperture which is normally closed by a 20 cover and which may only be opened when the switch has been manipulated to break the circuit.

Objects of the present invention are to provide an improved switch of the above type 25 of simple and inexpensive character and having few essential parts; of compact construction such that it may be installed in the space usually available for this purpose; effective to prevent theft of current at all times even 30 when the fuse is exposed to view; affording the requisite degree of safety to the user; and easy to operate and of pleasing external appearance.

In the accompanying drawings a preferred 35 embodiment of the improved switch is illustrated by way of example;

Fig. 1 is a front elevation of the improved switch with the parts in the position which they occupy when the current is turned on;

40 Fig. 2 is a side elevation of the switch with the parts in a similar position;

Fig. 3 is a fragmentary front elevation of the switch with the parts in the position which they occupy when the circuit is broken and 45 with the fuse aperture open to permit renewal of the fuse plug.

Fig. 4 is a front elevation showing the switch box open to expose the circuit-closing elements;

50 Fig. 5 is a transverse section to larger scale substantially on the line 5—5 of Fig. 1, some of the parts being omitted;

Fig. 6 is a side elevation of the base plate

upon which the fuse-supporting means and the movable switch elements are mounted; 55

Fig. 7 is a rear elevation of the device shown in Fig. 6; and

Fig. 8 is a diagram illustrating the wiring connections leading to and from the improved switch. 60

The improved switch comprises a box-like container 1, preferably of metal or other strong and durable material, and comprising the side walls 2 and 3, the rear wall 4, and the top and bottom walls 5 and 6. The 65 container may conveniently be made of pressed sheet metal, although the exact construction of the container forms no essential feature of the present invention.

This container is provided with a front 70 wall or cover 7, preferably hinged at 8', and having an aperture in its free edge through which may project a lug 7^a secured to the side wall 2 of the container, such lug having an opening through which the wire 7^b of a sealing device 7^c may be passed. Any other suitable means for normally locking or sealing the cover in closed position may be employed.

A base plate 8 (Figs. 5, 6 and 7), preferably of insulating material, is secured by 80 suitable fastening means, as for example the rivets 9, to the inner surface of the rear wall 4 of the container. The central part of the rear side of this base plate is preferably cut away so that the plate bears against the wall 85 4 only along its marginal portions 10. The central part 11 of the base plate is thus spaced from the inner surface of the wall 4 of the container for a purpose hereinafter described.

The base plate 8 is furnished with a centrally disposed aperture whose axis is substantially perpendicular to the wall 4 of the container, and a bracket member of substantially U-shape is journalled to turn in this opening. This bracket is preferably formed 95 of sheet material and comprises the spaced parallel legs 12 and 13 connected at one end by the member 14 and having oppositely directed ears 15 and 16 respectively at their free ends.

A metallic washer 17 is preferably set into the surface 11 of the plate 8, such washer being concentric with the journal opening in the plate. A lever arm 18, which is disposed in the space between the wall 4 and 105 the under surface 11 of the plate 8, projects

into the loop formed between the legs 12 and 13 of the U-shaped bracket and is secured to the member 14 by a screw 19. A spring washer 20 is disposed between the washer 17 and the inner surface of the arm 18. A washer 21 is disposed at the opposite side of the base plate 8 beneath the ears 15 and 16, and the resiliency of the spring washer 20 is such as to take up any lost motion between the parts while permitting the U-shaped bracket to turn in its journal opening.

A support 23, preferably of insulating material and preferably though not necessarily of generally frusto-conical form, is mounted upon the ears 15 and 16. Any suitable means may be employed for attaching the larger end of this support to the ears.

The smaller end of the support 23 is furnished with an axial bore or socket 24 for the reception of a fuse receptacle having relatively insulated contact elements, of which the metallic shell 25 constitutes one, and the screw head 26 constitutes the other. The screw of which the head 26 forms a part has threaded engagement with an axial opening in the support 23 and thus retains the receptacle in proper position. This receptacle is adapted to receive a fuse plug 29 of any usual type having the terminal members 27 and 28 which make electrical contact with the members 25 and 26 respectively of the receptacle.

A metallic switch element 30, preferably of blade-like form, is secured to the support 23, preferably by clamping it between the base of the support and one or both of the ears 15 or 16. This switch blade is connected electrically to the contact element 26 of the receptacle, preferably by permitting the screw, of which the contact element 26 forms the head, to have threaded engagement with the blade 30.

A second switch element 31, also preferably in the form of a blade, and preferably extending in a direction diametrically opposite to the blade 30 passes through a suitable opening in the side wall 23 and makes electrical contact with the member 25 of the receptacle. This blade 31 is insulated from the contact 26 by means of suitable washers 32 and 33.

The base 8 supports the fixed switch elements 34 and 35 (Figs. 5 and 6) which are adapted respectively to engage the blades 30 and 31 in one predetermined angular position of the support 23. Preferably these fixed contacts 34 and 35 comprise opposed resilient members, such for example as the spring elements 34^a and 34^b (Fig. 6) between which the blades 30 and 31 enter to make proper contact between the parts. Suitable conductors 36 and 37 are connected to the switch elements 34 and 35, the arrangement described being such that when the switch elements are engaged and the fuse 29 is properly seated a continuous electrical connection

is provided between the conductors 36 and 37.

The cover 7 of the box preferably comprises a piece of sheet metal turned in at its edges to provide flanges overlapping the sides of the box proper and having at its central part an annular guard member 43, preferably of frusto-conical shape, which projects inwardly from the plane of the main body of the cover. This guard member 43 may be integral with the body of the cover and formed by a stamping or punching operation or constructed as here shown from a separate piece of metal having an attaching flange 44 secured to the body of the cover in any appropriate manner, for example by brazing or spot-welding. This guard 44 defines a funnel-like opening 38 leading inwardly from an aperture 38^a in the body of the cover, such funnel-like opening constituting a chamber for housing the fuse block.

The underside of the cover is provided with suitable guide flanges 39 for guiding a sliding closure plate 40 which normally closes the entrance to the opening 38.

The funnel-like opening 38 is coaxial with the journal opening in the base plate 8 and when the cover 7 is in closed position the inner or smaller end of the opening 38 is closed by the outer end of the support 23. The outer end of the support 23 is preferably of reduced diameter as indicated at 41, thus providing an annular shoulder 42 and the reduced portion of the support preferably projects into the funnel-like opening 38.

The smaller end of the guard 43 is turned in to provide an annular flange 45 which surrounds the forward end portion 41 of the support 23 and cooperates with the shoulder 42 to prevent insertion of a conducting element through the aperture 38^a and into contact with any of the switch elements.

A handle comprising a substantially straight central portion 46 is journalled to turn in an opening in the side wall 2 of the box. Preferably a bracket 46^a is provided at the inner side of the wall 2 having a supplementary journal opening for the member 46 whereby to steady the latter. This handle also comprises an arm 47 disposed within the box and having a member 48 which engages an elongate opening 49 (Fig. 6) in the outwardly projecting end 50 of the lever 18. The handle also comprises a hand grip arm 51 constituting the actuating member disposed outside of the box and which is guided in its swinging movement by means of a bracket 52 having a slot 53 in which the member 51 oscillates.

The closure plate 40 is furnished with a part 54 which projects out through the side wall 2 of the box and in some positions of the handle member 51 the latter lies in the path of the member 54 and thus prevents the closure plate 40 from being withdrawn to uncover the aperture 38.

The top wall 5 of the box is furnished with an aperture having an upstanding flange 55 to which the usual meter 56, indicated in broken lines, is secured. This meter comprises the usual series coils 57 and 58 and the potential coil 59 and is interposed between the switch and the distributing lines H^1 and H^2 . The switch-conductors 36 and 37 are connected, either directly or indirectly, to the power lines P^1 and P^2 . When the switch is closed and the fuse plug is in proper condition, current is admitted through the switch and meter to the distributing lines H^1 and H^2 .

When the switch is closed, the handle member 51 occupies the position shown in Figs. 1, 2 and 5, and in order to swing the handle to this position whereby to close the switch it is necessary first to push the closure plate 40 inwardly thereby covering the aperture 38^a.

When it is necessary to replace the fuse plug the handle member 51 must first be swung to the position shown in Fig. 3 thus opening the switch before the closure plate 40 can be withdrawn.

The device thus provided is of simple and compact construction, and contains but few operative parts, and these parts are of a character such that they can be manufactured very cheaply and readily without the use of special machinery. At the same time the device provides effective means for preventing theft of current and safety to the user.

I claim:

1. In a device of the character described the combination of a casing having a sealable cover provided with an aperture, a switch mounted on the wall of said casing opposite said cover having its terminals accessible when said cover is open, said switch comprising a switch arm adapted to oscillate about an axis in line with the center of said aperture to open and close said switch, said switch having a non-conducting member preventing access through said aperture to the terminals of said switch when said cover is closed, a fuse mounted on said non-conducting member and removable and replaceable through said aperture, a closure for closing and opening said aperture, and means for locking said closure in closed position whenever said switch is closed and releasing said closure when said switch is open.

2. In a device of the character described the combination of a casing having a sealable cover provided with an aperture, a switch mounted on the wall of said casing opposite said cover having its terminals accessible when said cover is open, said switch comprising a switch arm adapted to oscillate about an axis in line with the center of said aperture to open and close said switch, said switch having a non-conducting member preventing access through said aperture to the terminals of said switch when said cover is closed, a fuse mounted on said non-conducting mem-

ber and removable and replaceable through said aperture, a closure for closing and opening said aperture, and means for locking said closure in closed position whenever said switch is closed and releasing said closure when said switch is open, said fuse being a plug fuse having its axis in line with the axis of oscillation of said switch arm.

3. In a device of the character described the combination of a casing having a sealable cover provided with an aperture, a switch mounted on the wall of said casing opposite said cover having its terminals accessible when said cover is open, said switch comprising a switch arm adapted to oscillate about an axis in line with the center of said aperture to open and close said switch, said switch having a rotatable non-conducting switch arm carrying member preventing access through said aperture to the terminals of said switch when said cover is closed, a fuse mounted on said non-conducting member and removable and replaceable through said aperture, a closure for closing and opening said aperture, and means for locking said closure in closed position whenever said switch is closed and releasing said closure when said switch is open, said cover having a re-entrant portion through which said non-conducting member protrudes.

4. A device of the class described comprising a base plate having a journal opening therein, a member rotating in said opening, a frusto-conical insulating support attached at its larger end to said rotary member and having an axial bore in its smaller end, a fuse receptacle seated in said bore, oppositely directed relatively insulated switch blades carried by the support, fixed switch members mounted upon the base cooperable with the respective switch blades, electrical conductors connected to the fixed switch members, and means for turning the support.

5. A device of the class described comprising a box, a base plate secured to the inner surface of one wall of the box, the central part of the plate being spaced from said wall, the plate having a journal opening therethrough, a member rotating in said opening, a lever arm disposed between the inner surface of said wall of the box and the rear side of the plate, said arm being secured at one end to one end of said rotating member and having an elongate opening at its other end, a support mounted upon the forward end of the rotating member, a fuse receptacle and switch element carried by the support, and a handle outside of the box having an inwardly extending arm engaging the elongate opening in the lever arm for turning the support.

6. A device of the class described comprising a base plate having a journal opening therethrough, a U-shaped bracket having parallel legs, said legs being disposed within the opening in the base and constituting an axle

for the bracket, a lever arm attached to the closed end of the bracket and extending substantially parallel to one face of the base, attaching ears projecting oppositely from the 5 free ends of the legs of the bracket and extending substantially parallel to the other face of the base, a support attached to said ears, a fuse receptacle mounted on the support, switch blades carried by the support, 10 relatively fixed switch elements cooperable with the respective blades, and means engaging the lever arm to turn the bracket.

7. A device of the class described comprising a box, a rotary support inside of the box, 15 a fuse plug and switch element mounted upon the support, a lever arm carried by the support, a handle member comprising a straight central part journalled in an opening in the wall of the box, the handle having portions 20 substantially at right angles to said central part, one of said portions being outside of the box, and a fixed bracket on the outside of the box having an elongate slot for guiding the latter part of the handle, the other of said 25 handle portions being inside of the box and engaging the lever arm whereby oscillation of the handle turns the support.

8. A device of the class described comprising a normally closed container, a fuse receptacle within the container, said receptacle being spaced inwardly from one wall of the container, the container having a circular aperture in said wall coaxial with the fuse receptacle, an annular guard mounted upon 30 and projecting inwardly from said wall, said guard being coaxial with the aperture and at its inner edge embracing the receptacle, a closure for the aperture, an oscillating circuit controlling switch having its axis in line with 35 the center of said aperture, and means locking said closure in closed position so long as the switch is positioned to complete the circuit the axis of said fuse receptacle being fixed relatively to said opening.

45 9. A device of the class described comprising a normally closed and locked container provided with openings for the admission of electrical conductors, terminals for such conductors disposed within the container, a fixed 50 base within the container, a rotary support mounted on the base, said support having a circular portion and a peripheral shoulder, means for rotating the support, a fuse receptacle carried by the support in concentric relation to the axis of rotation thereof, one wall 55 of the container having an aperture coaxial with said axis, and an annular guard mem-

ber secured at one edge to said wall in concentric relation to said aperture and axis and having its opposite edge closely embracing the circular portion of said support and overlying the peripheral shoulder of the latter, said support entering one end of said annular guard and having its axis of rotation fixed 60 relatively thereto.

65 10. A device of the class described comprising a container, a removable cover therefor having an opening, a rotatable member in the container carrying a fuse receptacle and the movable members of a switch, the axis of rotation of said rotatable member being concentric with said opening, the fuse receptacle being positioned at the opening in the cover and closing said opening when the cover is 70 closed, a supplemental cover adapted when closed to prevent access to the fuse and fuse receptacle, and a switch operating member accessible outside of the container and adapted to oscillate said rotatable member in said opening to open and close the switch, said switch operating member having a part cooperating with the supplemental cover to prevent the latter from being opened when the rotatable member is in switch closing position, the axis of said rotatable member being fixed 75 relatively to said aperture.

80 11. A device of the class described comprising a container, a removable cover therefor having an opening, a rotatable member in the container carrying a fuse receptacle and the movable member of a switch, the axis of rotation of said rotatable member being concentric with said opening, the fuse receptacle being positioned at the opening in the cover and closing said opening when the cover is 85 closed, a supplemental cover adapted when closed to prevent access to the fuse and fuse receptacle, and a switch operating member journalled in the wall of the container for oscillation on an axis at right angles to the axis 90 of the rotatable member, accessible outside of the container and adapted to oscillate said rotatable member in said opening to open and close the switch, said switch operating member having a part cooperating with the supplemental cover to prevent the latter from being opened when the rotatable member is in 95 switch closing position, the axis of said rotatable member being fixed relatively to said aperture.

100 110 Signed by me at Cambridge, Mass., this 8th day of May, 1925.

GRANVILLE E. PALMER.
